UNITED STATES PATENT OFFICE

170,446

POWER BUTTER CHURN

Hilaire Blanchette, Drummondville, Quebec,
Canada, assignor to La Compagnie J. A. Gos-
selin Limitee, Drummondville, Quebec, Canada

Application December 10, 1952, Serial No. 22,618

Term of patent 14 years

(Cl. D23—1)

To all whom it may concern:

Be it known that I, Hilaire Blanchette, a Canadian citizen, resident of the city of Drummondville, Province of Quebec, Canada, have invented a new, original, and ornamental Design for a Power Butter Churn, of which the following is a specification, reference being had to the accompanying drawing, forming part thereof, wherein:

Figure 1 is a three-quarter front perspective view of a power butter churn showing my new design and,

Figure 2 is a three-quarter rear perspective view thereof.

The appearance of the side of the butter churn, opposite to the side shown in the drawing, is the same.

I claim:

The ornamental design for a power butter churn, as shown and described.

HILAIRE BLANCHETTE.
